UNITED STATES PATENT OFFICE.

JAMES A. BURDEN, OF TROY, NEW YORK.

MACHINE FOR MAKING HORSESHOES.

SPECIFICATION forming part of Letters Patent No. 624,622, dated May 9, 1899.

Application filed March 3, 1898. Serial No. 672,423. (No model.)

To all whom it may concern:

Be it known that I, JAMES A. BURDEN, of the city of Troy, county of Rensselaer, and State of New York, have invented new and useful

5 Improvements in Machines for Making Horseshoes, of which the following is a specification.

My invention relates to machines for making horseshoes, and more particularly to improvements upon the machine designed for 10 this purpose which is described and shown in Letters Patent No. 524,307, granted to me August 14, 1894, and in which a wheel provided with peripherally-located dies is employed and operated to move with alternating 15 periods of motion and rest, during each of which periods of rest a blank is bent around one of the die-frogs of the die-wheel and at a succeeding period of rest is top-swaged and has its heel ends compressed. In the machine 20 described in the before-named Letters Patent and to which my invention herein shown is illustrated as applied a projecting bar is operated to enter a recess formed in the toe end of each of the die-frogs, with the outer face of 25 this bar at its entering end projecting beyond the toe end of the frog, so that when a blank is bent thereon it will at its toe end be in advance of the frog, and thus leave a space between the inner edge of the bent blank and 30 the toe end of the frog, wherein the metal subsequently displaced laterally by top-swaging or concaving the shoe may enter, and so prevent the formation of a fin thereat, my improvement upon the said projector being to 35 combine with it a bar to bear directly upon the outer face of the blank when the latter is resting on the entered blank-projector and being bent thereon to hold the blank firmly in place.

40 My invention also relates to a means whereby the entered blank will be adapted to automatically adjust itself with uniformity to the operation of the frog-dies and the benders with accuracy.

45 Accompanying this specification to form a part of it there are three plates of drawings, containing ten figures, illustrating the application of my invention, with the same designation of parts by letter reference used in all 50 of them.

Of the illustrations, Figure 1 is a perspective of a horseshoe-machine with my improve-

ments shown as applied thereto and with that side of the machine at which the blanks are entered shown as facing the view. Fig. 2 is 55 a perspective of that part of the machine whereat the blank is entered to be acted upon, showing also part of the die-wheel and benders and with the combined blank-projector and blank-holder omitted. Fig. 3 shows in 60 side elevation part of the die-wheel, one of the frog-dies, with the blank-projector and combined blank-holder, shown as having entered the recess formed in the toe end of one of the die-frogs and the blank-holder as bearing on 65 the outer face of the blank, with that part of the die-wheel shaft which is shown being illustrated in cross-section. Fig. 4 is an end view of the combined blank-projector and blank-holder and the stock in which it is mounted, 70 with that end of the apparatus which engages with the blank shown as facing the view. Fig. 5 is a section taken on the line $x'x'$ of Fig. 4. Fig. 6 is a perspective of the bar forming the blank-holder and part of the blank-projector 75 shown as detached from the stock in which it is mounted. Fig. 7 is a top view of the blank-projector, shown as detached. Fig. 8 is a view of the under side of the blank-projector. Fig. 9 is an elevation of one of the dies, with 80 a blank shown as resting on the blank-projector, with the latter shown in section, taken on the line x^2x^2 of Fig. 5. Fig. 10 shows the position of the blank after having been bent around the frog, in advance of the toe end of 85 the latter, and with the blank-projector and combined blank-holder removed.

The several parts of the apparatus thus illustrated are designated by letter reference, and the function of the parts is described as 90 follows:

The letters F designate the frame or housing of the machine and in which the working parts are mounted.

The letter J' designates the main driving- 95 shaft, which is actuated by a pulley. (Not shown.)

The letters G² designate a gear-wheel mounted on the driving-shaft, and J² another shaft, on which there is mounted the gear-wheel G', 100 with the latter arranged to mesh into the gear-wheel G² on the driving-shaft to receive power therefrom.

The letters G³ designate beveled gears, of

which there is one at each side of the machine mounted upon the driving-shaft J' , and the letters G^4 designate another beveled gear-wheel at each side of the machine, each of which is provided with a vertical shaft and arranged to mesh into the beveled gear-wheel G^3 at each end of the driving-shaft to thereat operate said vertical shafts to actuate a side swager, which is not shown.

10 The letters $O O$ designate benders, each of which is pivoted to an oscillating frame part, which latter is operated by the cams O^3 on the shaft J^2 . Each of these benders at its lower end is provided with a roller r^3 and is arranged 15 to run in a curved guide, as will be more fully detailed hereinafter.

The letter J^4 designates the die-wheel shaft, and W the die-wheel.

The letter R designates a double ratchet-wheel arranged on the outer end w^4 of the die-wheel shaft where extended through and beyond its bearing in the machine-housing.

The letter V designates a pawl-holder arranged eccentrically on the shaft J' ; by which 25 the ratchet-wheel is actuated to move the die-wheel shaft with intermittent periods of motion and rest.

The letters D designate the frog-dies, which are arranged on the flat faces d^3 of the die-wheel and of which but one is shown at Fig. 3. These frog-dies are shown as detached from the die-wheel at Figs. 9 and 10 and as mounted on the flat faces of the die-wheel at Figs. 1, 2, and 3.

35 The letters B designate a blank in a position to be bent, and B^2 a blank after having been bent around one of the frogs d^2 by the operation of the benders $O O$, with the blank when bent resting upon the flat surface d^3 of the die proper where encircling the sides d^5 of the frog and its toe end d^4 .

The letter N designates an angular recess which is formed in the toe end of the die-frogs d^2 , and this recess is cut out of the frog at its 45 toe end to extend through the latter to the top of the die-plate d^3 , all of the before-named parts being of the same construction that is shown in the before-named Letters Patent No. 524,307.

50 The letter P designates the combined blank projector and holder, constructed with the angularly-formed upper surface p^2 , the bottom angularly-formed surface p^3 , and the vertical surface p^4 , which latter is upwardly projected 55 from the top of the angularly-formed top p^2 , as shown at Figs. 4, 5, and 6. This combined blank projector and holder is operated to have the bottom angular face p^3 adapted to enter the angular recess N , formed in each of the 60 die-frogs, as they come to a period of rest, with the upper angular face p^2 projecting beyond the toe end of the die-frog, so that when a blank is entered it will rest on the angular top p^2 of the projector, while the vertical face p^4 will bear against the outer face of the blank to hold the latter firmly in place while being bent. When the blank is thus

bent, so that at the toe end of the die the blank is in advance of the frog, there is a space C^4 , having a crescent form, between the 70 toe end of the frog and the bent blank, into which space when the shoe is concaved or swaged on top the metal displaced laterally will enter this space, and thus prevent the forming of a fin thereat. This combined 75 blank projector and holder is mounted on the inner end and bottom of the stock S , which latter is recessed at e^3 on its under side to receive it, and it is produced by means of a plate M , having formed thereon at each of 80 its ends the angular projection p^3 , adapted to enter the recess N , formed in the die-frog, and the plate I , made with the opening i^2 at each of its ends, the bolts $b^6 b^6$ connecting the bottom plate M and the intermediately placed plate I with the stock, the plates M and I being made alike at both ends, so as to make them each reversible.

The letter L designates an L-form bar having formed on its horizontal part l^2 the angular projection p^2 and the vertical blank-holder surface p^4 , upwardly projected from the angular projection p^2 . This bar L is provided with beveled sides, whereby it may be entered in a vertically-arranged keying-recess formed in the inner end of the stock, 95 so as to rest on the top of the plate M at m^3 .

To operate the combined blank holder and projector P , the following mechanism is used: The letter A designates an arm which at its 100 upper end is mounted upon and keyed to the rock-shaft S' and by which latter the lower end of said arm A is operated to swing inwardly toward and outwardly from the die-wheel. The letter H designates a bracket 105 which is made vertically adjustable to the lower end of said arm A by means of a slot S^2 , formed in said bracket, a bolt b^3 , connected to said arm, arranged in said slot and thereat provided with a nut n^8 , threaded onto 110 said bolt. The stock S is journaled onto the bracket H at h^2 by means of the pintle-shaft h^3 and is arranged to rest upon the offset a^3 of the bracket when the combined blank projector and holder is by the arm A operated 115 to move inwardly to engage with the die-frog and blank. The rock-shaft S' is provided with bearings b' in the offset-brackets b^{11} on the machine frame or housing, and at its end opposite to that at which the bar A connects 120 with this rock-shaft the latter is provided with a crank-arm A^6 , which at its upper end is provided with a roller arranged to engage with the cam-wheel a^8 on the shaft J^2 . When the arm A actuates the combined blank projector and holder to move inwardly, it so operates it while the die-wheel is at one of its 125 periods of rest, with the angular projection p^3 entering the recess N , formed in the die-frog, which is in position to be operated upon, with the angular projection p^2 extending beyond the toe end of the die-frog, and the holder part p^4 in position to have a blank pass down 130 behind it to have the blank rest on the pro-

jection p^2 before the combined blank projector and holder has completed its inward movement, which when completed causes the holder-surface p^4 to engage with the outer face of the entered blank, so as to hold it securely against the die-face at the toe end of the frog while the blank is being bent. As soon as the bending is completed and the wheel commences to move, the stock S, resting upon the offset a^3 , is free to rise when being drawn outwardly and to again descend on the offset to be operated upon in the same manner when a succeeding die comes into position with the die-wheel at rest and another blank is inserted, the intermediate periods of motion and rest given to the die-wheel and frog-dies being timed to have the arm A actuate the blank-projector and blank-holder the moment the die-wheel stops and to have the blank entered just before the combined projector and holder have completed their inward movement.

The letters $O^2 O^2$ designate two disks, of which there is one mounted on the inner end 25 of each of the bars r^2 , with each of the latter connected to an offset-ear e^4 , formed on the bar b^3 , each adjustably connected to the housing at c^5 . These disks O^2 are each free to rotate on the rods r^2 , on which they are placed 30 between the nut n^3 on their inner end and the nut n^4 on the rod r^2 outside of the disk.

The letter T^2 designates a stop which is of a disk form and which is rigidly connected to the inner end of the bar t^2 , which is threaded 35 into the ear t^3 and adjustably secured thereon by the jam-nut n^5 . The function of these disks O^2 and the stop T^2 is to furnish an automatically-adjusting means for the proper placing of the blank, so as to insure the production of uniform work, and this result is 40 accomplished by having the entering end of the blank abut against the vertical face of the stop T^2 and with the blank between its ends placed upon the disk-wheels $O^2 O^2$, which 45 by their adjusting rotation will guide the blank in its descent edgewise to rest centrally on the inwardly-moving projector P when entering the recess N, with the ends of the blank resting upon the teats k , of which there is one 50 formed on the outer face of each of the plates k^2 , projected outwardly from each of the bender-arms A ^{2} and in front of where the latter are projected downwardly below the benders proper to run in the curved guideways g^5 , 55 the blank being placed upon the projector before having completed its inward movement and before the holder part p^4 of the projector has engaged with the blank to hold it while being bent.

60 The benders O O at their upper ends are pivotally mounted in a frame part F ^{2} , which latter at its lower end f^5 is journaled on a horizontal shaft f^6 , with the frame part F ^{2} operated to be oscillated on its journaled connection by the cams O ^{3} O ^{3} and by which movement of said frame part the benders pivoted thereto are together operated to descend and

rise, with their lower ends moving in a curved direction by the guides g^5 . These benders, as well as the stop T ^{2} , have the same construction that is shown in said Letters Patent No. 524,307, and apart from their being a part of a new combination I make no claim therefor herein. As the adjusting disk-wheels O ^{2} O ^{2} can be used in connection with the stop T ^{2} to 70 perform useful functions, I do not limit my invention to their combination with the combined blank-projector and blank-holder with which I herein illustrate them as arranged to 75 co-operate.

I am aware that it is not new to employ a blank-holder and blank-projector separately constructed and separately operated, my improvement being limited to forming and operating them connectedly.

Having thus described my invention, what I claim, and desire to secure by Letters Patent, is—

1. The combination with a wheel provided with frog-form dies on its peripheral face, with 90 each of the frog-form dies having a recess formed in its toe end; of means whereby said wheel is operated to rotate with alternating periods of motion and rest; a blank-projector actuated to enter a recess in each of the toe 95 ends of each of the frogs in succession when at rest, so as to project beyond the toe end of the frog, and having a holder part integrally formed with said projector part, and at right angles thereto, and constructed to move with 100 it, and bear against the outer face of the blank being bent upon the projector part, the die, and the frog, substantially as shown and described.

2. The combination with a wheel provided 105 with frog-form dies on its peripheral face, each of the frogs having a recess formed in the toe end; said wheel being actuated to rotate with alternating periods of motion and rest; of a blank-projector actuated to enter 110 the recess of each of the frogs in succession when at rest, so as to extend beyond the toe end of the frog, and having formed integrally with said projector and at right angles thereto 115 a holder-bar operated to move with said projector, and arranged to bear on the outer face of the horseshoe-blank while being bent; and benders moving in guides and operated to engage with the entered blank to bend the same 120 around the frog in which the projector is entered while the blank is being held in position on the die-face by the holder, substantially as shown and described.

3. The combination with a wheel provided 125 with frog-form dies, of means substantially as described whereby said wheel is rotated with alternating periods of motion and rest; a stop having a vertical face arranged at one side of the said die-wheel; a disk wheel at each side of the latter having their rims in 130 horizontal alinement, and projecting beyond the die-wheel; said disk wheels being adapted to adjustably rotate, whereby a horseshoe-blank being placed thereon with one of its

- ends abutting against said stop will by the action of gravity and the rotation of said disk wheels be carried downwardly to have its center rest upon the toe end of the frog; and benders operated to engage with the blank so placed to bend it around said frog-form die substantially as shown and described.
4. The combination with a wheel having frog-form dies on its peripheral face, with the frog of each of said dies provided with a recess in its toe end, said wheel being actuated to rotate with alternating periods of motion and rest, of a blank projector and holder actuated to move inwardly to enter the recess 10 of the adjacent frog, when at rest, and to bear upon a blank when the latter is being bent on said projector and frog; a stop at one side of said die-wheel; a disk wheel at each side of said die-wheel arranged to project beyond 15 the perimeter of the latter with the rims of said disk wheels in parallel horizontal alignment; whereby a blank placed on said disk wheels will by the adjusting rotation of the latter be deposited upon the recess-entering 20 blank-projector between the die-face and the blank-holder, before the latter has reached the limit of its inward movement; and benders actuated to bend the blank so entered upon the projector and frog substantially as 25 shown and described.
5. The combination with the wheel W, having the dies D, each made with a frog d^2 , that

is provided with a recess N in its toe end; of the blank-projector P, constructed and operated to enter the recess N, of each of the 35 frogs, when coming into position and to project beyond the toe end of the frog; said blank-projector being provided with a blank-holder bar L, having the surface p^4 , and the benders O, O, constructed and arranged to 40 be operated substantially as shown and described.

6. The combination with the wheel W, having the dies D, each made with the frog d^2 , that is provided with a recess N, in its toe end; 45 of the blank-projector P, constructed and operated to enter the recess N, of each of the frogs, when coming into position, and to project beyond the toe end of the frog, said blank-projector being provided with a blank-holder 50 bar L, having the surface p^4 ; the stop T²; the adjustably-rotating disk wheels O², O²; and the benders O, O, constructed and arranged to be operated substantially as and for the purposes set forth.

Signed at the city of Troy, New York, this 1st day of March, 1898, and in the presence of the two witnesses whose names are hereto written.

JAS. A. BURDEN.
